UNITED STATES PATENT OFFICE

MOYE W. SPRUILL, OF PLYMOUTH, NORTH CAROLINA

SHOE SHINING MACHINE

Application filed August 28, 1930. Serial No. 478,414.

This invention relates to shoe shining machines and one object of the invention is to provide a machine of this character having mechanism driven by an electric motor the circuit of which cannot be closed until a coin is dropped into a coin receiving chute by a person desiring to have his shoes shined.

Another object of the invention is to prevent the machine from operating until a person occupies a seat forming part of the machine and to further provide the circuit for the motor with a switch adapted to be closed when a person's foot is in position for shining a shoe. By this arrangement, operation of the motor will not take place prematurely and, in addition, the current will be shut off while one foot is being removed and the other set in place and waste of the cleaning and polishing fluid will be prevented.

Another object of the invention is to permit only a measured quantity of cleaning and polishing fluid to be dispensed each time a coin is placed in the coin slot and thereby prevent too much fluid from being dispensed and also permit the shoes to be air dried while being brushed to form a polish after the fluid has been applied to them.

Another object of the invention is to provide the machine with brushes so mounted that all portions of a shoe may be operated upon and thoroughly cleaned and polished and to also so locate nozzles for the fluid dispensing means that fluid may be applied to all portions of a shoe. By this arrangement, thorough cleaning and polishing of all portions of a shoe will be insured.

Another object of the invention is to provide a machine of this character which will be compact in construction, and very efficient in its operation.

The invention is illustrated in the accompanying drawings, wherein:

Figure 1 is a perspective view of the improved machine.

Figure 2 is a longitudinal sectional view

through the machine, taken on the line 2—2 of Figure 3.

Figure 3 is a longitudinal sectional view taken horizontally through the machine.

Figure 4 is a transverse sectional view 50 taken on the line 4—4 of Figure 3.

Figure 5 is an enlarged fragmentary sectional view illustrating the position occupied by a coin when dropped into the coin chute.

Figure 6 is an enlarged transverse sectional view taken on the line 6—6 of Figure 3.

Figure 7 is a fragmentary perspective view of a portion of the mechanism for actuating the front brush.

Figure 8 is a diagram of the energizing circuit for the motor.

Referring to Figure 1 of the drawings, it will be seen that this machine includes, briefly, a casing or housing 1, in which polish applying and shining mechanism are mounted as shown in Figures 2 and 3, a pedestal or hollow support 2 in which the coin chute and the container for the polishing fluid and control means for dispensing the fluid are located, and a seat 3 to be occupied by a person desiring to have his shoes shined. The pedestal or support 2 is open at its upper end beneath the seat and in order to support the seat there has been provided tubular columns 4 disposed vertically in the pedestal 2 with their lower ends secured upon the bottom 5 of the pedestal and rods or plungers 6 slidably received in the columns. These plungers 6 rest upon springs 7 in the columns in order to yieldably resist downward movement of the plungers and the upper ends of the plungers are connected with the boards 8 of the seat by screws or equivalent fasteners 9. It will thus be seen that the seat will be yieldably supported and may be pressed downwardly by the weight of a person occupying the seat. An opening 10, through which a person's foot may pass, is formed in the top of the casing 1 and, at one side of the

60

70

75

80

85

90

seat, is mounted a block 11 having a coin slot 12 formed therein.

Within the casing 1 there is disposed a platform 13 mounted in an elevated position above the base board 14 of the casing and resting upon supporting tubes or columns 15 through which are passed securing rods or bolts 16, each of which may have securing nuts at both ends or a head at one end and a securing nut at its other end. This platform is disposed beneath the opening 10 and carries seats or supports 17 and 18 upon which the heel and sole of a shoe rest when a person's foot is passed through the opening 10 in order that a shoe may be shined. Between the seats 17 and 18 an opening 19 is formed in the platform and through this opening extends the plunger of a push button switch 20. This plunger is yieldably held in a raised or opened position and is intended to be pressed downwardly by a person's foot in order to close the switch when a person's foot is in position to have a shoe shined. By this arrangement, a circuit for the motor can be closed only when a person's foot is resting upon the seats 17 and 18 and operation of the motor will be cut off while one foot is being removed and another passed through the opening 10 into position to rest upon the seats. Brushes 21 to operate upon the sides and back of a shoe are mounted above the platform for movement longitudinally thereof and a brush 22 to operate upon the front and toe portion of a shoe is mounted above the forward portion of the platform for movement transversely thereof. By this arrangement, all portions of a shoe may be brushed, during a cleaning and polishing operation.

The brushes 21 are securely but removably mounted in clamps 23 which are loosely connected with the arms 24 of a yoke 25 by studs 26 and in order to yieldably resist movement of the brushes relative to the arms of the supporting yoke, there have been provided springs 27 which are secured to the arms and bear against the clamps. By this arrangement, the brushes will be pressed into yieldingly engagement with a person's shoe and also will be permitted to have rocking movement as the brushes are moved longitudinally of the platform and the bristles of the brushes will have proper engagement with the shoe as the brushes reciprocate. A block 28, to which the yoke 25 is secured, rests upon tracks or bars 29 extending longitudinally beneath the platform and supported by brackets 30 and in order to retain the block or carriage upon the tracks there has been provided a cross bar 31 secured against the block with its ends projecting therefrom and engaging the under faces of the tracks, as shown in Figure 6. Therefore, the block or carriage may move longitudinally upon the tracks without becoming detached therefrom and it cannot have binding engagement with the tracks as

it is held against twisting movement by its engagement with the tracks.

The brush 22 is mounted in a manner similar to the brushes 21 and is removably secured in a clamp 32 loosely connected with the inwardly bent upper end of a bracket 33 by studs 34 and yieldably held against movement relative to the bracket by a spring 35, corresponding to the springs 27. This bracket 33 has its lower end fastened upon a block or carriage 35 resting upon tracks or bars 36. These tracks extend transversely of the platform with their ends secured upon brackets 37 and a bridge or bracket 38, and by an inspection of Figure 3, it will be readily seen that the brush 22 will have movement transversely of a shoe across the front and toe portions thereof, whereas the brushes 21 will have movement longitudinally of the shoe against the sides and heel portions thereof. Movement of the brushes must be so timed that there will be no danger of interference by the brushes striking each other during their movement. A cross bar or plate 39 corresponding to the cross bar or plate 31 is secured against the under face of the carriage 35 with its end portions extending beneath the tracks 36 in order to retain the carriage upon the tracks and guide sliding movement of the carriage.

In order to impart reciprocating motion to the carriages 28 and 35, there has been provided shafts 40 and 41 mounted in bearings 42 at right angles to each other and their adjacent ends carry intermeshing beveled gears 43 so that rotary motion may be transmitted to the shaft 40 from the shaft 41. Discs 44 and 45 are firmly fixed to the shafts 40 and 41 and to these discs are pivotally connected pitman bars 46 and 47, the other ends of which are connected respectively to the carriages 28 and 35. Therefore, when the shafts 40 and 41 are rotated the pitmen which have connection with the discs 44 and 45, will impart reciprocating motion to the carriages and the brushes 21 will be moved longitudinally of the platform in proper timed relation to movement of the brush 22 which reciprocates transversely of the platform. The motor 48 is secured firmly upon the base boards 14 with its shaft 49 extending parallel to the shaft 41 and the motor shaft is joined to a shaft 50 projecting from a gear housing 51. Within the gear housing, the shaft 50 carries a worm meshing with a worm gear carried by a shaft 52 which projects from the housing at right angles to the shaft 50 and is rotatably mounted in bearings 53. This shaft carries a bevelled gear or pinion 54 meshing with a companion gear or pinion 55 on the shaft 41 and it will be readily understood that by this arrangement, rotary motion will be transmitted from the motor shaft to the shaft 41 at a reduced rate of speed.

The wire 56 from one side of the motor

is attached to the stationary contact 57 of the switch 20 and the wire 58 leading from the contact 59 carried by the plunger of the switch is secured to a coin chute 60 mounted in the pedestal 2 in substantially vertical position, as shown in Figure 4, with its upper end communicating with the slot of the coin block 11. This chute is formed of conductive material as is also an abutment or contact 61 carried by a rocker arm 62 pivotally mounted in the pedestal by a depending strip or bracket 63. The other end of the rocker arm is forked as shown at 64 for engagement with a pin 65 projecting from a depending arm or bracket 66 secured to the chair board 8 of the seat. Under normal conditions, the springs 7 support the seat in such a position that the contact 61 will be spaced below the lower end of the coin chute a sufficient distance to permit a coin to pass from the chute and drop into the coin box 67 but when a person occupies the seat, the weight of the person will depress the seat, thereby causing the rocker arm to swing about its pivot and move the contact 61 upwardly from the position shown in Figure 4, to that shown in Figure 5. When this movement takes place, the contact 61 will be disposed close to but out of engagement with the lower end of the coin chute and when a coin 68 is dropped into the chute it will rest upon the contact 61 and be prevented from dropping into the coin box until the person occupying the seat rises and the springs 7 return the seat and the rocker arm 62 to their initial position. Since this coin 68 engages the coin chute as well as resting upon the contact 61 to which the power wire 69 is attached, a circuit may be established through the motor and the motor energized as soon as the plunger of the switch 20 is pressed downwardly to move the contact 59 into engagement with the stationary contact 57. It will thus be seen that the motor cannot be energized without dropping a coin through the coin chute and also that as long as the coin is supported as shown in Figure 5, the motor may be energized by pressing the plunger of the switch downwardly and when a foot is removed the motor will be shut off until the push button switch is again closed. The power wire 69 and the other power wire 70 will be of sufficient length to extend out of the casing and have their outer ends connected with a plug for engagement with a wall socket or they may be connected with a socket mounted in a wall of the casing to receive a plug carried by wires leading from a suitable source of current.

Cleaning and polishing fluid is to be applied to the shoes during the cleaning and shining operation and this fluid is stored in a tank or reservoir 71 mounted in the pedestal 2, the level of the liquid in the tank being kept below the level of the spray noz-

zles to prevent overflow through the nozzles. An outlet pipe 72 leads from the bottom of the receptacle into a valve 73 supported in an upright position by a base 74 attached to the bottom or flooring 5 of the pedestal. 70 This valve is normally open and is provided with a stem 75 which projects upwardly and is connected with an arm or bar 76 secured to the chair board 8 and extending downwardly therefrom. By this arrangement, pressure 75 will be applied to the stem 75 when the seat is depressed by the weight of a person occupying the same and the valve will be shut as long as a person is seated upon the seat or chair. 80

A pipe 77 connected with the outlet of the valve extends forwardly at one side of the pedestal and then longitudinally of the base 1 at one side of the table or platform 13, as shown in Figure 3. Small tubes 78 and 79 lead from the pipe 77 near its forward end and by an inspection of Figure 3 and Figure 2, it will be seen that the tubes 78 extend upwardly at the front of the table or platform and carry nozzles 80 projecting diagonally toward the support or seat 18 from opposite sides thereof, whereas the tube 79 extends upwardly at the back of the platform and carries a nozzle 81 extending toward the heel seat 17. By this arrangement the cleaning and polishing fluid may be sprayed upon front and rear portions of a shoe and also upon bristles of the brushes 21 and 22. The valve 73 being open when the seat or chair is unoccupied, the cleaning and polishing 90 liquid will fill the pipe 77 and rise in the pipes 78 and 79 to the level of liquid in the tank 71 which is kept below the level of the nozzles, as before stated, so that the liquid will not unaided flow through the nozzles. 100 It is, therefore, necessary to supply pressure and in order to do so, there has been provided a tank 82 from which extends a pipe 83 connected with a check valve 84 having communication with the pipe 77 by means of a coupling 85. Pipes 86 provided with check valves 87 opening toward the tank, connect the tank with pumps 88 secured upon the base boards or floor of the casing 1 by clamps 89 and these pumps extend one longitudinally of the casing and the other transversely thereof. The piston rods 90 of the pumps are attached to brackets 91 and 92 carried respectively by the yoke 25 and carriage 35 and it will be readily understood 110 that when the carriages are reciprocating upon the tracks 29 and 36, the pumps will be operated and air forced into the air tank 82. Instead of having the pipes 86 provided with check valves 87, the air tank may be provided with inlet necks or tubes to which the pipes 86 are coupled and check valves similar to those used in the inflating tubes of tires may be mounted in the inlet necks of the tank. By 120 this arrangement, air will be pumped into the 130

tank and this air will flow from the tank through the pipe 83 past the check valve 84 into the pipe 77 and serve to force the cleaning and polishing fluid through the pipe 77 and out through the tubes 78 and 79 and their nozzles 80 and 81. The check valve 84 prevents fluid from being sucked back through the pipe 83 and also prevents fluid from flowing through this pipe by force of gravity 10 when the valve 73 is open.

When this machine is in use, a quantity of cleaning fluid is poured into the tank or reservoir 71 through an opening 93 formed in the chair board 8, it being understood that the 15 seat will be removed or tilted out of the way during the operation. A person desiring to have his shoes shined occupies the chair 3 and his weight causes the chair to be depressed. When this takes place, pressure will 20 be applied to the valve stem 75 in order to close the valve 73 and the rocker arm 62 will be tilted upon its pivot in order to move the contact 61 into such position below the lower end of the coin chute that when a coin 25 is dropped into the chute, it will rest upon the contact and establish electrical connection between the wires 58 and 69. One foot is then thrust through the opening 10 until it rests upon the seats 17 and 18 and the instep 30 portion of the shoe will depress the plunger of the switch 20 in order to make contact between the contacts 59 and 57. As soon as these contacts are in engagement with each other the circuit will be closed and the motor 35 energized. During operation of the motor, the shafts 40 and 41 are rotated and reciprocating motion will be imparted to the brushes 21 and 22 and also the pumps 88 will be operated. These pumps force air under pressure 40 into the tank 82 from which it passes through the pipe 83 and check valve 84 into the pipe 77 in order to force the cleaning and polishing fluid through the tubes and nozzles. The fluid is delivered from the nozzles in 45 sprays whereby to cause the shoe and the bristles of the brushes to be sprayed with the fluid. The brushes thoroughly and evenly distribute the fluid upon the shoe to insure proper cleaning of the shoe. After a sufficient quantity of fluid has been applied to one shoe, the foot is removed and the other foot thrust through the opening into place. During the interval one foot is being removed and the other put in place, the switch 50 55 20 will open, thereby shutting off the motor and preventing waste of fluid. After the second shoe has had fluid applied thereto, it is removed and by this time all of the fluid will have been used as only a measured quantity is contained in the pipe 77. The first foot is then again thrust through the opening 10 into place and as the brushes move across the front and toe portions of the shoe and sides and rear portion thereof to produce 60 65 a shine, air will be delivered through the no-

zles in order to thoroughly dry the shoe and bristles of the brushes if they are not already dry. When the first shoe has been polished to the satisfaction of the person occupying the chair, the other foot is thrust into place and the other shoe polished in a similar manner. The person then rises from the chair and the springs 7 restore the seat to a raised position which causes the valve 73 to again open so that the pipe 77 may again fill with 70 cleaning fluid. At the same time, the rocker arm 62 returns to the position shown in Figure 4 of the drawings and the coin drops into the coin box. By this arrangement, it will be seen that the machine cannot be operated again until another coin is dropped into the coin slot while, at the same time, first one foot and then the other may be thrust through the opening 10 in place and the machine will not operate until the foot is in the proper 80 position.

What is claimed is:

1. A shoe shining machine including, a foot support, a seat to be occupied by a person yieldably supported in a normal position and adapted to be depressed by the weight of a person occupying the seat, a container for liquid shoe dressing, a pipe leading from said container and having branch pipes leading therefrom and provided with nozzles adjacent the foot rest and above the normal level of liquid in the container, a valve for said pipe normally open and having operating means connected with the seat for actuation thereby to close the valve when the seat is depressed and means controlled by pressure of a shod foot on the foot support for delivering air under pressure to the pipe leading from the dressing container at a point beyond the valve therein whereby to spray dressing upon a shoe and subsequently deliver air thereon to dry the dressing. 90

2. A shoe shining machine including, a foot support, a seat to be occupied by a person yieldably supported in a normal position and adapted to be depressed by the weight of a person occupying the seat, a container for liquid shoe dressing, a pipe leading from said container and having branch pipes leading therefrom and provided with nozzles adjacent the foot rest and above the normal level of liquid in the container, a valve for said pipe normally open, means to close the valve when the seat is occupied and depressed, an air tank, a pipe leading from said tank to the first-mentioned pipe just beyond the valve therein, a check valve in the second pipe to prevent flow of liquid into the air tank, pumps for delivering air to said tank, polishing elements arranged to engage a shoe on the foot rest, and means controlled by pressure from the shoe on the foot rest for operating said polishing elements and the pumps whereby dressing will be sprayed 100 105 110 115 120 125 130 135 140 145 150

upon the shoe and an air-blast subsequently delivered thereon to dry the dressing.

3. In a shoe shining machine, the combination of a liquid polish metering chamber, 5 nozzles directed toward a shoe positioned in the machine, pipes connecting the nozzles to the metering chamber, and means to deliver air under pressure to the metering chamber to force polish from the metering 10 chamber onto a shoe supported in polishing position and then deliver an air-blast to dry the polish.

In testimony whereof I affix my signature.
